US0D1027939S

(12) **United States Design Patent** (10) **Patent No.:** **US D1,027,939 S**
(45) **Date of Patent:** **** May 21, 2024**

(54) **TABLET COMPUTER**

(71) Applicant: **Realme Mobile Telecommunications (Shenzhen) Co., Ltd.**, Shenzhen (CN)

(72) Inventor: **Bingxin Liu**, Shenzhen (CN)

(73) Assignee: **Realme Mobile Telecommunications (Shenzhen) Co., Ltd.**, Guangdong (CN)

(**) Term: **15 Years**

(21) Appl. No.: **29/831,677**

(22) Filed: **Mar. 22, 2022**

(30) **Foreign Application Priority Data**

Oct. 8, 2021 (CN) 202130659762.3

(57) **CLAIM**

The ornamental design for a tablet computer, as shown and described.

DESCRIPTION

FIG. 1 is a perspective view of a tablet computer showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the tablet computer that form no part of the claimed design.

1 Claim, 8 Drawing Sheets
